Inventor:

F. C. Hagan
PER *M. M. & C.*

United States Patent Office.

F. C. HAGEN, OF CUBA, NEW YORK.

Letters Patent No. 91,931, dated June 29, 1869.

IMPROVED BED-BOTTOM.

The Schedule referred to in these Letters Patent and making part of the same.

To all whom it may concern:

Be it known that I, F. C. HAGEN, of Cuba, in the county of Allegany, and State of New York, have invented a new and improved Bed-Bottom; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved bed-bottom.

Figure 2 is a plan or top view of the same.

Figure 3 is a vertical transverse section of the same.

Similar letters of reference indicate corresponding parts.

This invention relates to certain improvements in spring-bed bottoms, whereby the same are made more durable and convenient, and more easy to repair.

The invention consists in dividing the frame into three compartments, by transverse partitions, the central compartment, containing the springs, being covered by the hinged cushion, and the two end compartments, by means of head-and foot-cushions, that are adapted to be removed and changed to form the head or foot at either end of the frame, as will be herein-after more fully described.

A, in the drawing, represents the frame of my improved spring-bottom. In it are arranged the springs B B, in suitable manner.

Two cross-partitions C C, are arranged in the frame A, near the ends of the same, to divide the frame into three compartments, those at the ends being but narrow.

D is the cushion by which the springs are covered.

This cushion is arranged on a frame, a, which is hinged to the frame A, as shown in fig. 3, so that by swinging the frame a open, the springs B will be uncovered, and the under side of the cushion brought in position for inspection or repair.

The cushion D and its frame a only extend over the middle compartment, which is formed between the partitions C.

The end compartments receive separate head and foot-cushions, E and F, respectively.

These latter cushions are formed on frames of suitable construction, and are placed upon the frame A, and locked thereto by suitable means. They are both of equal width, as well as the end compartments.

The head and foot-cushions can therefore be readily reversed, when it is desired to change the bed, or when one side of the main cushion should have become more compressed than the other.

Having thus described my invention,

What I claim as new, and desire to secure by Letters Patent, is—

The bed-bottom, constructed, as described, of the frame A, divided into three compartments by the transverse end partitions C C, the central compartment, containing the springs B, being covered by the hinged cushion D, and the two end compartments by the removable head and foot-cushions E F, all arranged as described, for the purpose specified.

F. C. HAGEN.
